UNITED STATES PATENT OFFICE.

HARRY C. POWERS, OF NEW YORK, N. Y., ASSIGNOR TO DORETTA POWERS, OF NEW YORK, N. Y.

DESIGN FOR A BOTTLE.

No. 39,371.

Specification for Design.

Patented June 23, 1908.

Application filed February 5, 1908. Serial No. 414,452. Term of patent 7 years.

To all whom it may concern:

Be it known that I, HARRY C. POWERS, a citizen of the United States, and whose residence and post-office address is 68 Bay Twenty - sixth street, Bensonhurst, New York, in the county of Kings and State of New York, have invented a new, original, and ornamental Design for a Bottle, of which the following is a specification, reference being had to the accompanying drawing, forming a part thereof.

The figure is a view in elevation of a bottle showing my design.

In order that those skilled in the art may be enabled to make and use the invention, I describe the same in detail. The design of bottle shown comprises a glass receptacle in

the shape of a cigar, with one end open for the reception of a stopper. The outer surface of the glass receptacle has formed thereon ridges to simulate the veins of leaf tobacco; and as a covering I use a wrapper of foil closely wrapped so that an impression is made through the foil by the ridges that may be visible to the eye. A cigar band surrounds the bottle, as shown.

I claim:

The ornamental design for a bottle as shown.

HARRY C. POWERS.
